UNITED STATES PATENT OFFICE.

JAMES H. BUCHANAN, OF LOS ANGELES, CALIFORNIA.

INTERNAL-COMBUSTION HEATING SYSTEM.

1,264,005.

Specification of Letters Patent. Patented Apr. 23, 1918.

Application filed April 29, 1916. Serial No. 94,515.

To all whom it may concern:

Be it known that I, JAMES H. BUCHANAN, a citizen of the United States, residing at Los Angeles, in the county of Los Angeles 5 and State of California, have invented new and useful Improvements in Internal-Combustion Heating Systems, of which the following is a specification.

This invention relates to internal combustion heating systems, and it has for its object to provide improvements of this general character which will be applicable to a wide range of uses and in which many of the objectionable features of heating systems, as heretofore organized, will be eliminated.

In accordance with the present invention, the combustible gas and the air necessary to support combustion, are both supplied to a suitable combustion head and thence the products of combustion are delivered to a coil, radiator, or the like which is completely closed as against invasion by the air of a room. An exhaust pipe is provided 20 to conduct the products of combustion away from the coil and out of the room or chamber in which the coil or radiator is installed. By the provision of electrical ignition means for the combustible fuel and air 25 all necessity of communication with the interior of the system, save through the supply means and exhaust pipe is eliminated, and such system cannot possibly discharge products of combustion into that portion of 30 the medium being heated or draw on such portion of the medium being heated for any fraction thereof to assist in supporting combustion. The system is shown as installed and applied to the heating of the interior of 35 a room or building, though many other useful applications of the invention will readily suggest themselves, such as the heating of liquids and the like by the provision of a suitable vessel or the like adapted to contain 40 such liquids and surrounding the coil or radiating portion of the system. It is also evident that the coil or radiating portion of 45 the system may be placed in contact with or proximity to any other substance or device 50 to be heated.

A further object of the invention is to provide apparatus of the general character stated which will be relatively simple and inexpensive in construction and installation, 55 not liable to get out of order or repair, which will be highly efficient, and which will be

generally superior in point of reliability and serviceability.

With the above and other objects in view, the invention consists in the novel and useful provision, construction, combination, association and interrelation of parts, members and features, and mode of operation, all as hereinafter described, shown in the drawing, and finally pointed out in claim.

In the drawing:

Figure 1 is a fragmentary side elevation of a heating system constructed, organized and installed in accordance with the invention, the same being shown as installed in a building, the fragment of a wall and of a floor being shown in section;

Fig. 2 is a central vertical sectional detail view of certain features of the invention shown in Fig. 1, the view being upon an enlarged scale; and,

Fig. 3 is a fragmentary plan view of a multiple unit system constructed and organized in accordance with the invention.

Corresponding parts in all the figures are designated by the same reference characters.

Referring with particularity to the drawing, in the embodiment of the invention therein shown, A designates a combustion chamber, shown as in the form of a radiator, B designates the combustion head thereof, C designates air supply means, D designates fuel supply means, E designates ignition means, and F in Fig. 1 designates control means for the air supply means. C. 90 G in each instance designates control means for the air supply means in Fig. 3.

The combustion chamber A is shown as a pipe coiled intermediately of its ends as at a', and threaded into the head B as at 4. 95 The pipe a terminates in an exhaust portion 5 at the end opposite the combustion head B, such exhaust portion being shown as passed through an aperture 6 provided in a wall 7 of a room in which the combustion chamber A is installed. 8 designates the floor of such room.

The combustion head B is shown as comprising a tubular body b provided with a branch b' and internally threaded at one end as at 9 to receive the threaded end 4 of the pipe a forming the combustion chamber. The other end of the tubular body is preferably internally threaded as at 10 to receive a reducing bushing 11. The reducing bushing 11 110 is provided with a threaded aperture 12 to receive a burner tube 13 provided with an

externally threaded enlargement 13^a taking into the threads at the aperture 12, so as to provide adjustment in the combustion head B, for the burner tube 13. A lock nut 14 secures the burner tube in place. The branch b' is internally threaded at its terminus as at 15 to receive the threaded end 16 of a pipe 17 comprised within the air supply means C. The tubular body B is 10 provided with an aperture 18 slightly above the burner tube 13, which is preferably centrally located therein, a spark plug 19 being threaded into such aperture 18 as at 19^a. The organization of the spark plug will be 15 well understood when it is stated that a plug such as is used in igniting the combustible charge in gas engines may be employed, such plug being provided with an electrically grounded spark point 20 and an 20 insulated spark point 21. The insulated spark point 21 is formed on the end of a rod 22 extending through the insulation 23 of the spark plug.

The air supply means C preferably comprises the supply pipe 17, a blower or the like 24 which may be driven by motor 25 directly coupled therewith, and a suction or intake pipe 26, which may be provided to conduct incoming air to the blower. The air 25 supply pipe 17 may extend through an aperture 17^a provided in the floor 8 and is connected at one end with the discharge 24^a of the blower, and at the other end, as before stated, with the branch b' of the combustion head B as at 16. The blower and the motor therefor may be of standard construction.

The fuel supply means D is shown as comprising a gas pipe 27 leading from a suitable source of supply and passed through an orifice provided in the floor 8 and terminating in a control valve 28 preferably placed slightly below the combustion head B and connected with the receiving end 13^a of the burner tube 13.

The ignition means E may be of any preferred form suitable for igniting gas and air admitted into the combustion head B, and is shown as comprising a switch, push button, or the like 29 provided in a primary electric circuit 30 which circuit may include a battery or other source of supply of electrical energy 31, and extends through the primary winding 32 of an induction coil e, 55 a secondary electrical circuit 33 which may comprise a portion of the gas pipe 27, one of the circuit wires 33^a being connected to such gas pipe as at 33^b, and the spark plug 19 described in connection with the combustion head B. A circuit wire 34 of the secondary circuit is connected with the insulated rod 22 of such spark plug.

The control means F for the air supply means C is shown as an electric switch controlling the flow of electricity through the

circuit wires 35 and 36 supplying the motor 25. Such switch may be arranged to cut off the circuit wires 35 and 36 from the supply wires 37 and 38, respectively, or to connect the circuit wires 35 and 36, respectively, 70 with such supply wires 37 and 38 which may lead from any suitable source of supply of electrical energy.

In Fig. 3 a plurality of combustion chambers A, each being connected with the attendant features B, air supply pipe 17, fuel supply means D, and ignition means E are shown. A main air supply pipe of which the plurality of air supply pipes 17 are branches, is provided. Such main supply 75 pipe 17^a may be supplied with air under pressure by the blower or the like 25 being connected therewith and motor driven as described in connection with the other figures. A common gas supply pipe d is provided 80 and is branched to provide the supply pipes 27, one leading to each of the combustion heads B. A common exhaust duct or pipe 39 is provided, to which all of the exhaust portions 5 of the respective pipes a' forming 85 the combustion chambers A, are connected. Each unit may be provided with ignition means organized like the ignition means hereinbefore described.

The air supply control means G may each 90 comprise a valve 40 which the respective pipe 17 is interrupted to receive. A valve 41 may be provided in each of the pipes a in the exhaust portions 5 thereof.

The operation, method of use and advantages of the improved internal combustion heating system will be readily understood from the foregoing description, taken in connection with the accompanying drawing and the following statement:

Where the air supply control means are organized as at E, the throwing of the switch to supply electrical energy to the motor 25 will result in the driving of the blower 24 by the motor 25, and the forcing 100 of air under a slight pressure through the pipe 17 into the combustion head B, where gas supplied under control of the valve 28 mingles with the incoming air and is ignited by a spark at the spark points 20 and 21 105 resulting from actuation of the button or switch 29 to close the battery circuit through the induction coil e to generate such spark. As long as the supply of air and gas is properly regulated, the combustion thereof will 110 proceed, the products of combustion escaping through the discharge portion 5 of the pipe A of which such radiator or coil is formed. The supply of air and gas may be regulated to provide the required heat. 115 Upon opening of the switch F the blower will cease to supply air and upon closing of the valve 28 the gas will be shut off, thus 120 putting the apparatus out of operation. It is, of course, understood, that in the heating 125 130

of air in a room by means of a heating system organized in accordance with the invention, the heat is imparted to such air by radiation from the outside of the pipe *a* and the air is not vitiated by products of combustion escaping into the room, nor is the air in the room depleted of oxygen as all air required to support combustion is supplied through the supply pipe 17 from a source outside of the room being heated.

In the multiple unit system shown in Fig. 3 the air supply is controlled, with respect to each unit, as required, by means of the valve 40 and the gas supply is controlled through the respective valve 28. The valve 41 in the exhaust portion of the pipe *a* may be opened when the respective unit is in operation, and, may if desired, be closed to shut off communication with the common exhaust duct 39 when the unit is put out of operation. It is evident that any one of the units shown in Fig. 3 may be independently operated or all such units may be operated

together, the only requirement being that a sufficient supply of air under slight pressure be maintained in the common supply pipe 17^a.

Having thus disclosed my invention, I claim and desire to secure by Letters Patent:

The combination with a chamber, of a heating apparatus located therein and closed against communication therewith, comprising a closed head, a heating coil connected to said head and opening outside of said chamber, means for forcing air from outside of said chamber into said head, means for supplying gas to said head, and electric means arranged to ignite the mixture in the closed head, substantially as described.

In testimony whereof, I have signed my name to this specification in the presence of two subscribing witnesses.

JAMES H. BUCHANAN.
